UNITED STATES PATENT OFFICE.

ARNOLD STEIGER AND WILHELM STEIGER, OF ZURICH, SWITZERLAND.

GAS-FIRED SHAFT-KILN FOR BURNING OR ROASTING NON-SINTERING SUBSTANCES.

1,317,603.

Specification of Letters Patent. Patented Sept. 30, 1919.

Application filed December 18, 1918. Serial No. 267,305.

To all whom it may concern:

Be it known that we, ARNOLD STEIGER and WILHELM STEIGER, citizens of the Republic of Switzerland, residing at Rämistrasse 6, Zurich, Switzerland, have invented certain new and useful Improvements in Gas-Fired Shaft-Kilns for Burning or Roasting Non-Sintering Substances; and we do hereby declare the following to be a clear, full, and exact description of the invention, such as will enable others skilled in the art to which it appertains to make and use the same, reference being had to the accompanying drawings, and to letters or figures of reference marked thereon, which form a part of this specification.

This invention relates to a gas fired shaft kiln for burning or roasting lime, magnesite, iron ores, other ores and other non-sintering materials, which is adapted to be heated by means of producer gas, waste gases from blast furnaces or other combustible gases.

In view of the difference in quality of the material which is burnt, it is necessary to vary the treatment, so as to insure the most satisfactory results. In most cases, success of the operation depends entirely on the manner in which the charge is caused to descend in the shaft and on a good and appropriate supply of combustion air.

The object of the present invention is to provide a gas fired shaft kiln of the kind referred to, in which the contents are loosened to a high degree in the cooling zone in order to provide an unobstructed passage for the air of combustion which in the furnaces hitherto proposed was forced to rise along the walls of the furnace.

A further object of the present invention is to provide a gas fired shaft kiln in which the material in the cooling zone is subjected to less friction than in the kilns known hitherto, the formation of dust and the breaking up of the material into small pieces being consequently much reduced. This is of very great importance for the treatment of certain materials, as is the case, for instance, for the treatment of quick lime for the production of carbid.

A still further object of the invention is to provide a shaft kiln sufficiently perfect to overcome without substantial changes in construction, any subsequent occurrences, such as fluctuations and changes in the ma-

terial burnt or in the fuel, atmospheric conditions, method of working, etc.

In the gas fired shaft kiln according to this invention, the cross-section of the shaft kiln is suddenly increased in the cooling zone to a considerable amount at least at one point, preferably immediately beneath the combustion zone.

In the shaft kiln according to this invention, the loosening of the material in the cooling zone is then furthered by a discharging device which *per se*, is a known feeding device.

Further, in the shaft kiln according to the invention, the pressure conditions and the quantity of air pumped in by a compressor or blower and the cross-sectional area of passage of means leading the compressed air into the interior of the kiln, may be modified for the purpose of regulating the pressure and the escaping quantity of air.

In the shaft kiln according to the present invention, the air is also preferably supplied to the contents of the kiln at the maximum pressure through means arranged close to the sole of the kiln and at a smaller pressure through conduits arranged nearer to the combustion zone.

Moreover, the conduits are made so that each may be closed separately by means of throttling elements adjustable from the outside, and near the upper end of the kiln is arranged an air exhauster.

A construction according to this invention is illustrated by way of example in the accompanying drawings in which:

Figure 1 shows the kiln in longitudinal section;

Fig. 2 is a cross-section on the line II—II of Fig. 1;

Fig. 3 is a cross-section on the line III—III of Fig. 1 and

Fig. 4 is a cross-section on the line IV—IV of Fig. 1.

Referring to the drawings, A denotes the shaft of the kiln supported on four columns B. 1 denotes the pre-heating zone. The supply material to this zone is controlled by a charging hopper 4 of known design. 2 denotes the combustion zone and 3 the cooling zone of the kiln. The combustion zone 2 has the smallest cross-section of said three zones, while the cross-section of the cooling zone is suddenly increased to a considerable

amount at two points, namely once immediately beneath the combustion zone 2 and a second time in its lower half. 5 are channels provided in that part of the wall of kiln 5 which surrounds the upper half of the cooling zone. Each channel 5 communicates with the zone 3 by means of a port 6, the cross-sectional area of passage of which can be modified from the outside by means of a 10 throttling member 16. The channels 5 are connected to a gas supplying generator 17 by means of conduits 18. 7 is a blower forcing the air of combustion through the kiln. This blower 7 is connected by pipes 7^a to 15 small bustle pipes 7^b that supply nozzles 25 Figs. 1 and 2 which are distributed around the circumference of the kiln. In the construction illustrated, there are four such nozzles 25. The blower also delivers air through 20 the bustle pipes 7^b to valves 22, Fig. 2, that discharge into upward conduits 19 in the interior of the kiln wall having over a portion of their length a zig-zag shape. The conduits 19 discharge into channels 20 pro- 25 vided in the kiln wall surrounding the combustion zone 2. Each channel 20 communicates with short conduits 9 inclined downwardly into the kiln shaft. These conduits 9 closed on the outside by covers 23 are for 30 supplying additional combustion air to the combustion zone 2 when too little air is supplied to said zone through the conduits 18 and 5 and ports 6. The quantity of air passing from each channel 20 into the cor- 35 responding conduit 9 can be controlled by means of a sliding member 21 adapted to be adjusted from the outside. 22 (Fig. 2) are adjustable valves which are for controlling the pressure of the air passing into the conduits 19. 10 designates poke-holes.

At the upper end of the kiln A is arranged a pipe 8 communicating with the interior of the kiln and connected to an exhauster 24 for exhausting the gases above the stock 45 line.

In the bottom of the kiln are provided in the embodiment shown two outlet openings, the material being guided toward said openings by downwardly sloping surfaces 11. 50 Beneath each of said openings is arranged a discharging device comprising a stationary frame 12 with an obliquely situated portion 13 and a movable inclined bottom 14, to which a crank mechanism 15 imparts a to 55 and fro movement.

The speed of the blower 7 and of the exhauster 24 can be regulated by influencing their driving means.

The shaft kiln described hereinbefore 60 works as follows: The firing gases supplied to the channels 5 pass through the conduits 6 into the upper part of the cooling zone 3 and then into the heating zone 2, the most intensive combustion taking place in the 65 lower part of this zone 2. The contents sink-

ing from the latter into the cooling zone 3 are loosened in the latter to a high degree owing to the sudden increases of the cross-section of this zone immediately beneath the combustion zone 2 and in the lower part of the cooling zone. In consequence of this loosening of the material, the passage of the air forced by the blower 7 through the nozzles 25 into the cooling zone 3 is very much facilitated and the material is also subjected in this zone to lesser friction than in the kilns known hitherto, the breaking up of the material into small pieces and the formation of dust being consequently much reduced.

The compressed air produced by the blower 7 is supplied at the highest pressure through the nozzles 25 situated close to the kiln sole, and at a smaller pressure through the conduits 9 to the contents of the kiln. 85 By changing the speed of the blower, the pressure of the compressed air may be modified and by means of the needle valves provided in the nozzles 25 and the sliding members 21 the cross-sectional area of passage 90 of the apertures connecting the channels 20 to the conduits 9 may be adapted to the pressure of the compressed air used at the time, so that for instance, on the pressure being increased owing to a greater speed of the 95 blower, an increase of the quantity of air supplied to the interior of the kiln, may be avoided by throttling the quantity of air passing into the shaft.

The result of the compressed air being introduced at the maximum pressure close to the kiln sole, and of passages being formed through the charge in the same, is that the compressed air can reach the core of the column of the charge and assist the combustion there. Owing to the high pressure of the air at this point of introduction, a lowering of the fire by the compressed air introduced higher up, is avoided. The air introduced close to the sole of the kiln, passes 100 through the cooling zone, and thus uniformly cools the material burnt right through, while the said air, being forced to rise in the center of the kiln, is used for combustion in a highly heated state, owing 105 to which there is a substantial economy of fuel, and the output of the kiln is increased.

In the gas fired shaft kiln hereinbefore described the draft and the pressure conditions can be regulated at will and also the quantity of air required for combustion can be adjusted very exactly to the working conditions.

This avoids reduced fire and insufficient combustion or supply of air, owing to which the temperatures in the kiln are lowered, so that the result is a considerable increase of the output of the kiln with a reduced consumption of fuel. Owing to the above mentioned regulation, not only any desired ma- 125 130

terial, whether in large or small pieces, soft or hard, wet or dry, may be treated in the kiln, but also without the least constructional change, a number of low or high 5 grade fuels which would be out of the question without regulation, may be used.

As the air is supplied to the conduits 9 through the wall of the kiln, the air is heated on the way to the interior of the kiln 10 before it mixes with the combustion gases, so that the combustion is very favorably affected.

By a suitable regulation of the air supply, one-sided burning is avoided. Moreover, 15 owing to the graduation of the pressure toward the burning zone, the fire is not driven upward unnecessarily along the wall, as is the case, for instance, if air were to pass into the interior of the kiln through the conduits situated nearer the burning zone at the same pressure as at the bottom. In this 20 case there takes place a very quick and intense burning along the wall, while in the interior of the kiln it lags behind, which results in irregular burning.

The discharging devices 12, 13, 14, 15 arranged beneath the outlet openings provided in the bottom of the kiln have also the effect of furthering the loosening of the 30 contents in the cooling zone, the constant discharge of the burnt or roasted material taking place keeping the contents of the kiln in continual motion. The automatic discharging of the contents increases considerably the output of the kiln, as each of 35 the discharging devices 12, 13, 14, 15 may be adjusted so that the amount of material discharged corresponds just to the amount exposed to the action of the gas flames. 40 Thus, the contents do not remain in an entirely superfluous manner for several hours in the kiln after that they have been sufficiently burnt, as it is the case in the manually discharged furnaces; on the contrary, 45 the material of the combustion zone is slowly and continually replaced by the material sinking from the top toward the bottom, which results in an increased efficiency and saving of fuel.

50 The cross-section of the kiln can also be different from that shown, and any number of outlet openings and discharging devices may be provided. When requisite, the cross-section of the cooling zone 3 can also be suddenly increased at more than two points, while in some instances a sudden increase of 55 said cross-section only immediately beneath the combustion zone 2 is already sufficient for obtaining the desired effect.

60 We claim:

1. A gas fired kiln for burning or roasting non-sintering materials, comprising a vertical shaft consisting of a pre-heating zone, a combustion zone and a cooling zone, the 65 three zones being in vertical alinement and

the cross section of the cooling zone being suddenly increased to a considerable amount at least at one point, and means for supplying compressed air to said shaft, said means arranged to supply compressed air to the 70 cooling zone for pre-heating by the material contained therein while on its way to the combustion zone.

2. A gas fired shaft kiln for burning or roasting non-sintering substances, comprising 75 a shaft having a cross-section suddenly increasing in the cooling zone to a considerable amount at several points, so that the charge is suddenly loosened in said zone, means for supplying firing gases to said 80 shaft, means for supplying compressed air to said shaft, and an exhauster for exhausting the combustion gases from the shaft.

3. A gas fired shaft kiln for burning or roasting non-sintering substances, comprising 85 a shaft, a source of combustible gas arranged near said shaft, means for supplying the gases produced in said source to the shaft, a blower arranged beneath the shaft, conduits leading the compressed air from 90 said blower into the interior of the shaft, and adjustable means for controlling the pressure and consequently the quantity of compressed air supplied to the interior of the shaft by the blower and for adjusting the 95 cross sectional area of said conduits leading the compressed air into the interior of the shaft.

4. A gas fired shaft kiln for burning or roasting non-sintering substances, comprising 100 a shaft, a source of combustible gas, means for supplying the gases produced in said source to the shaft, a blower arranged beneath the shaft, conduits adapted to lead compressed air from said blower into the 105 interior of the shaft close to its sole, further conduits adapted to lead compressed air from said blower into the combustion zone of the shaft, and adjustable means to control the passage of the compressed air 110 through said conduits to supply air at a maximum pressure through said first mentioned conduits and at a less pressure through said conduits discharging into the combustion zone.

5. In a gas fired shaft kiln for burning or roasting non-sintering substances, the combination with a shaft comprising a pre-heating zone, a combustion zone and a cooling zone; of a source of combustible gases arranged near said shaft, conduits arranged in the wall of the shaft communicating with said source and adapted to supply the produced gases at the cooling zone of the shaft, means adjustable from outside the kiln for 115 regulating the quantity of gases passing from said source into the shaft, an air blower, conduits to lead compressed air from said blower into the interior of the shaft close to its sole, additional conduits ar- 120 125 130

ranged in the wall of the shaft to lead compressed air from said blower into the combustion zone of the shaft, and means adjustable from the outside of the kiln for controlling the quantity of compressed air supplied through said conduits into the shaft.

6. In a gas fired shaft kiln for burning or roasting non-sintering substances, comprising a shaft having a pre-heating zone, a combustion zone and a cooling zone, the cross section of said shaft increasing suddenly in the cooling zone to a considerable amount at several points, so that the charge 10 is suddenly loosened in said zone, a gas generator arranged near said shaft, conduits arranged in the interior of the wall of the shaft communicating with said generator and adapted to supply the combustion gases 15 produced in the generator into the upper portion of the cooling zone, means adjustable from the outside of the kiln for regulating the quantity of gases passing into the shaft, a blower arranged beneath the shaft, 20 means for regulating the speed of said blower, conduits for leading compressed air from said blower into the interior of the shaft close to its sole, additional conduits for leading compressed air from said blower 25 into the combustion zone of the shaft, adjustable means adapted to control the passage of the compressed air through said conduits whereby the air is supplied at a maximum pressure through said first mentioned conduits and at a less pressure 30 through said conduits discharging into the combustion zone, an exhaustor arranged at the top of the kiln for exhausting the gases from the pre-heating zone of the shaft, and 35 means for varying the speed of the exhaustor.

7. A gas fired shaft kiln for burning or

roasting non-sintering materials, comprising a vertical shaft having a pre-heating zone, a combustion zone and a cooling zone of 45 larger cross-sectional area than said combustion zone, and a second enlargement of cross-section at the bottom of said cooling zone.

8. A gas fired shaft kiln for burning or roasting non-sintering materials, comprising 50 a vertical up-draft shaft having a pre-heating zone, a combustion zone and a cooling zone abruptly enlarging in cross section below the combustion zone, means to supply combustible at the junction of the two last mentioned zones and means to supply air 55 intermediate the ends of the combustion zone.

9. A gas-fired shaft kiln for burning or roasting non-sintering materials, comprising 60 a vertical shaft having a pre-heating zone, a combustion zone and a cooling zone abruptly enlarging in cross-sectional area, and means to forcibly exhaust gases from above the stock line. 65

10. A gas-fired shaft kiln for burning or roasting non-sintering materials, comprising a vertical shaft containing a combustion zone and having a plurality of enlargements 70 in cross section below said zone, whereby the internal cross-section of the kiln increases by stages, means for supplying combustion gas at the bottom of the combustion zone, means for supplying air intermediate the ends of the combustion zone, means for 75 supplying air to the lowermost zone of largest cross-section to cool the material in this zone and simultaneously heat the air as it ascends through the material to the combustion zone. 80

In testimony that we claim the foregoing as our invention, we have signed our names.

ARNOLD STEIGER.
WILHELM STEIGER.
